UNITED STATES PATENT OFFICE

HENRY F. KURTZ, OF ROCHESTER, NEW YORK, ASSIGNOR TO BENNEVILLE LLOYD
SINGLEY, OF MEADVILLE, PENNSYLVANIA

DESIGN FOR AN INDICATING LAMP FOR AUTOMOBILES

Application filed January 31, 1930. Serial No. 34,354. Term of patent 14 years.

To all whom it may concern:

Be it known that I, HENRY F. KURTZ, a citizen of the United States, residing at Rochester, in the county of Monroe and State of New York, have invented a new, original, and ornamental Design for an Indicating Lamp for Automobiles, of which the following is a specification, reference being had to the accompanying drawing, forming part thereof.

Fig. 1 is a plan view of the lamp;

Fig. 2 is a side elevation thereof;

Fig. 3 is a front elevation thereof; and

Fig. 4 is a rear elevation thereof.

The dominant feature of the design consists of the use of a substantially semi-cylindrical portion one end of which merges smoothly at top and sides into a rectangular portion, while the other end is rounded or spherical, the whole being flared outwardly at the bottom to form a pleasing base or supporting flange.

I claim:

The ornamental design for an indicating lamp for automobiles, substantially as shown and described.

HENRY F. KURTZ.
